UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

PERFORATING MACHINE.

Application filed July 26, 1922. Serial No. 577,704.

To all whom it may concern:

Be it known that I, PERLEY R. GLASS, a citizen of the United States, residing at Wayland, in the county of Middlesex and State of Massachusetts, have invented certain Improvements in Perforating Machines, of which the following description, in connection with the accompanying drawings, is a specification, like reference characters on the drawings indicating like parts in the several figures.

This invention relates to punching machines and is herein illustrated as embodied in a machine for perforating parts of shoes for ornamental purposes.

It is common practice at the present time to perforate stock by feeding it between a punch plate and a reciprocating punch, a strip of paper being fed over the punch plate under the stock to act as a backing for the punch and insure clean cut perforations without damage to the punch. Such machines feed the paper at every stroke of the punch, usually under control of the punch, and are uneconomical of paper which is an expensive item. In my co-pending application Ser. No. 329,997, upon which Patent No. 1,448,210 was granted March 13, 1923, there is disclosed a machine and method which economizes in the use of paper backing by punching several times in the same area while the paper and punch plate are gradually lifted toward the punch to bring about a deeper penetration of the punch at each stroke thereby utilizing the entire thickness of the paper.

Objects of this invention are to provide a perforating machine which will allow still greater economies in the use of backing material and to simplify and otherwise improve machines of the type disclosed in said application without sacrificing any of the advantages of such machines as heretofore constructed. To these ends, in the illustrated machine, the punch is reciprocated a number of times against the same portion of the backing strip, which is clamped and retained at the same level during punching, and the strip is then fed forward under the control of the punch. Such a repeated punching in a single position with the strip held at a constant level is possible without reducing

the quality of the perforations since each prior punching lessens the resistance to the punch, which due to the inherent slight elasticity of the punch and punch plate supporting and actuating means, penetrates more and more deeply into the backing strip and thus utilizes the entire thickness. As shown, the backing strip is fed lengthwise and is also movable widthwise so that all three dimensions of the strip are utilized. As the quality of backing material is not uniform, the illustrated machine also provides for predeterminedly varying the number of reciprocations of the punch which take place against a given portion of the strip, thus allowing a larger number of punchings in a single position when the character of the strip permits. In the embodiment of the invention selected for illustration, the backing strip is led over a punch plate and kept under constant tension by a feed roller, there being a clamping member controlled by the machine for intermittently releasing the backing strip for feeding after the predetermined number of punchings. Preferably the punching mechanism is so organized that the punch controls both the feed of the work and the feed of the backing strip. As shown herein in my improved machine, the work feeding stroke is intermittently, after a variably predetermined interval, rendered effective to feed the paper also by mechanism which raises the backing strip so that the punch remains embedded therein during the work feeding stroke.

Other features of the invention relate to improved mechanism for actuating the punch, controlling and guiding the work, and otherwise improving the action of perforating machines generally.

Referring to the drawings:—

Fig. 1 is a side elevation of the machine with some parts removed and some in section;

Fig. 2 is a front elevation partly in section with the cover plate removed.

Fig. 3 is a perspective view of a portion of the front of the machine.

Fig. 4 is a vertical section of the punch plate and associated parts.

Fig. 5 is a perspective view of the swiveling punch and the device for returning it

to normal position at the beginning of each feed movement.

Fig. 6 is a perspective view of a portion of the front of the machine looking from the right and rear;

Fig. 7 is a perspective view of a work gage with a slightly modified positioning means;

Figs. 8 and 9 are detail views of a portion of the gage;

Fig. 10 is a perspective view of a portion of the front of the machine as seen from the left and front;

Fig. 11 is an exploded view of the punch plate and associated parts;

Fig. 12 is a vertical section through the feed roller and its driving means;

Fig. 13 is a vertical section of the punch and punch plate;

Fig. 14 is a perspective view, looking from the rear, of the variable speed driving mechanism, clutch and stop mechanism;

Fig. 15 is a vertical section of the same;

Fig. 16 is an exploded view, partly in section, of the clutch and stop mechanism; and

Fig. 17 is a perspective view of a detail.

The illustrated machine is of the type which employs a four-motion feed punch, there being in addition a slight relief movement of the punch preparatory to feeding the material. The machine comprises a frame 16 having a hollow arm 18 overhanging a circular work table 20, the work being fed rearwardly over the table away from the operator and in alinement with said overhanging arm. A vertical feed sleeve 22 is mounted for front to rear reciprocation in the overhanging arm and carries slidably the punch carrying sleeve 24, the latter having at its upper end a guide channel 26 formed by an upper flange 28 and a wear plate or shim 30. The punch carrying sleeve 24 is reciprocated vertically by mechanism comprising a block 32 slideable within the guide channel 26 and pivoted to the lower end of an arm on a lever 34 rockably hung on a pivot pin 36 of the frame. Between the upper end of the lever and an ear 40 (Figs. 2 and 3) on a loose hub on the pivot pin 36 is pivoted the front end of an actuating link 42, the rear end being pivoted to the upper end of a cam lever 44 which swings on a shaft 46 extending across the frame. The lower end of the cam lever is forked to embrace a three-way cam 48 on the main cam shaft 50. The cam 48 is formed in a manner to cause a punching movement followed by a dwell, a feed movement of the punch being effected by other mechanism during the dwell. The lower arm of the lever 34 which is hung at 36 is swung by the above described mechanism, from the position shown in Fig. 1 in which the punch is raised, to a position just beyond dead

center, this arrangement causing a slight rise or relief movement of the punch which will be hereinafter referred to.

The feed sleeve 22 has at one side a pair of horizontal sleeves 60 and 62 (Fig. 3) which are secured rigidly to upper and lower hollow guide rods 64 and 66 the ends of which slide in bearings 68 and 70 on the frame and in bearings 72 and 74 (Fig. 10) formed on a removable cover plate or cap piece 76 which closes the front of the hollow overhanging arm. At the rear of the feed sleeve 22 are two projecting ears 78 (the nearer of which may be seen in Fig. 10) between which is pivoted a link 80 extending rearwardly within the hollow arm (Fig. 1) and pivotally joined at its rear end to a block 84 slidably mounted in a channel formed on the far side of a rock arm 86 fixed to the rock shaft 88. A second arm 90 fixed to the rock shaft 88 is connected by means of a link 92 to the arm 94 of a lever pivoted at 96 to the frame and having between its ends a forked portion embracing a three-way cam 98 on the cam shaft 50. The cam 98 is so formed that it actuates the feed sleeve 22 when the punch is stationary and causes the feed sleeve to dwell when the punch is being reciprocated.

The work feeding stroke of the punch may be varied by sliding the block 84 in the channel of the rock arm 86, the channel being curved about the front end of the link 80 as a center so that adjustment of the feed does not affect the initial position of the punch. As shown, the block is pivotally connected by a link 100 to an arm 102 fixed to a rock shaft 104 which is actuated by a handle 106 (Fig. 3). Another arm 108 projecting from the rock shaft has at the end 109 a segmental surface 110 provided with gage marks for co-operation with an index bar 112 fixed to the frame. The arm 108 is slotted as indicated at 114 for the reception of a clamp screw 116 which holds it in adjusted position.

The punch may comprise a single punch 120 (Figs. 5 and 13) or a plurality of punches arranged in any desired pattern in a collet 122 which is detachably fixed by a clamp screw 124 in a head 126 carrying the swivelling punch spindle 128. Whatever the arrangement of the punches, the master punch indicated at 120 should be in alinement with the punch spindle, the remaining punches and the collet 122 being eccentrically disposed so that the work can be fed in a proper manner around curves as is well understood in the art. The head 126 is held from abnormal swivelling movement by a pin 129 projecting upwardly into a slot in the lower end of the punch carrying sleeve 24. The punch spindle is held within the sleeve by a nut 130 (Fig. 1) at the upper end. If, when operating on curved work, the punch is ro-

tated from normal position, it is restored to its original position at the beginning of each subsequent feed movement by means of a V-shaped notch 132 (Fig. 5) in the 5 spindle which contacts with a cam or wedge shaped surface on a plunger 134 slidably mounted in a square opening 136 in the cap piece 76. The plunger is pressed rearwardly by a spring 140 surrounding the shank 138 of the plunger and movement, under control of the spring, is limited by a nut on the outer end of the shank. In order for the plunger 134 to have access to the punch spindle, this plunger passes through an 10 opening in the feeding sleeve 22 and through a slot in the punch carrying sleeve 24 as indicated in Fig. 3.

For holding the work against the work support while the punch is being retracted 20 from the material, the following hold-down mechanism (best shown in Figs. 1 and 10) is employed: A presser foot bar 144 slideable in vertical bearings of the frame carries at its lower end a split sleeve 146 having a 25 horizontal rib on which slides horizontally the channel block 148, a clamp screw 150 holding this member in adjusted position. A hold-down 152 formed integrally with the block 148 lies against the work opposite the punch when the latter is at the beginning 30 of its feed stroke and is adjusted toward and from the line of feed of the punch by loosening the clamp screw 150 and adjusting the block 148. A second hold-down 154, 35 which extends around just to the rear of the punch when the latter is at its rearward limit of feeding movement, has a horizontal extension at the upper end which is slidably mounted in the block 148 and held in adjusted 40 position by the set screw 155. This second hold-down member 154, therefore, can be adjusted with the first hold-down 152 toward and from the line of feed of the punch and it also has an independent adjustment in the direction of the line of feed 45 so that, when the feed stroke of the punch is changed, the position of the hold-down 154 can be changed to correspond. The presser foot bar 144 is prevented from turning by a 50 slide block 156 fixed to the upper end of the bar and slideable in a groove of the overhanging arm. The bar 144 is actuated intermittently, in alternation with the reciprocation of the punch, by a roller 158 riding on a cam surface 160 at the upper end of the lever 34. A coiled spring surrounding the bar 144 keeps the hold-downs yieldingly against the work. To allow the operator to lift the presser foot bar when desired, there 55 projects from the bar a lift pin 162 engaged by an arm 164 of a lever pivoted at 166 on the frame and manipulated by a rod 168 connected to a foot treadle (not shown). A stop pin 170 on the frame limits the move- 60 ment of the arm 164 when the treadle is released.

As an aid to the controlling and guiding of the work, the following work-engaging members are provided. Projecting from the overhanging arm 18 is a bracket 180 (Figs. 1 and 6) on the rear side of which is slidably mounted a gage block 182, there being a slot through the bracket through which passes the adjusting screw 184 threaded in the gage block. To secure a fine adjustment of the gage block towards and from the line of feed of the punch, a hand screw 186 having a collar 188 interposed between lugs 190 on the bracket 180 is threaded into the gage block. The gage block has an inclined bearing 70 for the reception of a gage stem or spindle 192, the block being split as indicated at 196 to form in conjunction with the clamp screw 194 a clamping sleeve. When the clamping screw is loosened, the gage spindle may be turned to move the work engaging members to an out of the way position. By reason of the inclination of the stem, the attached work engaging members 80 will be raised from the work support as the spindle is turned. The gage spindle 192 has a groove 198 at the lower end receiving the edge of a collar 200 on a hand screw 202 by which the spindle may be raised and lowered. At the lower end of the spindle is a rigid gage arm 204 the end nearest the punch being of cylindrical formation (Figs. 8 and 9) and overlying the work support to 90 act as a guide for a slideable cylindrical casing or edge gage 206 for the work W, held down yieldingly against the work support by a spring 207 fixed to the gage arm and entering a slot in the casing. The edge gage can therefore yield upwardly when the punch plate is raised as hereinafter described. Swiveling movement of the gage arm in the line of feed is limited by means of a stop screw 208 which passes through a lug on the gage block 182 and abuts against the arm. A presser foot 210 (Fig. 2) in the form of a leaf spring is attached to the gage arm and is arranged to be adjusted toward and from the work support by the adjusting screw 212. It is apparent that by loosening the clamp screw 194 the edge gage may be turned in the line of feed to any desired position which can be fixed by means of the stop screw 208.

In Fig. 7 is illustrated a modified construction by which a fine adjustment of the work engaging members can be quickly secured. Reference numerals derived by adding 300 to those previously used designate parts analogous to those of Fig. 6. Projecting from the overhanging arm is a guide rod 480 having a U-shaped groove 481. Slidably on the rod is a small sleeve or adjustable member 484 which can be clamped in any 100 105 110 115 120 125

desired position by a clamp screw. A gage block 482 is likewise adjustable on the rod in a similar manner and is connected to the sleeve by a horizontal adjusting screw 486 5 of fine pitch. By loosening the clamp screws that hold the sleeve and the block to the guide rod, the block and sleeve may be quickly moved to approximately the position desired. By then clamping the sleeve 484 10 in position, the block 482 may be moved to the exact position desired by means of the screw 486 of fine pitch, above mentioned. Keys 491 in the groove 481 serve as abutments for the clamp screws and prevent the 15 sleeve and block from turning. The gage stem 492 is swivelled in the block 482 at an inclination and is adjustable vertically by nuts at the upper end. Swivelling is limited 20 by a stop screw 508 and the angular position is fixed by a clamp screw 494. This mechanism is of particular value when the character of work changes from that kind in which the perforations are close to the edge to a 25 different kind of work in which the perforations are widely spaced from the edge.

To avoid injury to the punches and to insure clean cut perforations, a backing surface such as a strip, preferably of paper, is provided and this strip is intermittently fed 30 over the punch block between the latter and the punch. A supply reel 218 (Figs. 1, 10 and 12) has a trunnion 220 mounted in a bracket 224 and held against too free rotation by a spring-pressed plug 222. The 35 backing strip extends over the punch block to a take-up reel 226 which maintains the strip under tension. The reel has a detachable flange (Fig. 12) which is held against the hub by a threaded sleeve 228 having a knurled head. The hub is splined to a shaft 232 journaled in the frame and loosely carrying a worm wheel 234 driven by a worm 40 236 on a worm shaft 238 driven in any suitable manner from the main cam shaft. 45 Leather, friction washers 239 are interposed between the worm and a pair of collars 240 and 242, the former being secured to the shaft by a set screw and the latter being splined thereon by a pin key. The leather, 50 friction washers are held against the worm wheel with the desired pressure by a coil spring interposed between the collar 242 and nuts 246 on the end of the shaft. There 55 is thus a constant tendency to turn the reel to feed the paper, but normally the paper is prevented from moving by a clamp device which will be hereinafter referred to. The supply reel and take-up reel are interchangeable.

60 As above stated, the punch has a four-motion feed and an additional movement of relief, that is, after the punch perforates the stock and penetrates the backing strip, it is withdrawn from the backing strip preparatory to feeding the work. Hitherto punch

feeding mechanisms employing a backing strip have fed the backing strip at every stroke of the punch. By this invention the relief movement of the punch is neutralized intermittently, so that it remains imbedded 70 in the strip to feed the latter at intervals, the frequency depending on the nature of the strip material. For instance, with a comparatively soft paper, four punchings might be carried out against 75 the same portion of the backing strip before the punch comes into undue proximity to the punch plate, whereas on harder paper it might be practical to punch eight or sixteen times against the same portion of the 80 strip. Mechanism is provided, therefore, by which the relief movement of the punch can be neutralized as frequently as desired and thus economize on paper to the fullest extent. Briefly, this movement is neutralized 85 by periodically raising the punch block and the backing strip so that the punch remains embedded in the backing strip during the punch feeding movement, thus causing the 90 strip to be fed under control of the punch.

An anvil 250 (Figs 4 and 11) arranged under the punch has at each side a guideway 252 in which is slidably mounted a cheek plate 254 projecting downwardly from a horizontal guide plate 256 having an oblong opening 258 surrounding the upper edge of the anvil. Guide flanges 260 on the guide plate project upwardly to guide the edges of the paper. Around the opening 258 in the guide plate there is formed a ledge 262 arranged to fit loosely the oblong punch plate 264 which may be of steel. A holding member or clamp plate 266 which is slotted and overlies the sides of the punch plate has vertical side flanges 268 secured by screws 270 to the cheek plates 254. The anvil has a slot 274 slightly elongated vertically to allow for relative movement of a pivot pin 272 passing through the cheek plates 254 and an arm 276 which is rigidly secured to a hub 278 loose on the rock shaft 280. The rock shaft 280 is journaled in a bearing sleeve 282 (Fig. 6) formed as a part of the anvil 250 and at one end the rock shaft has a depending arm 284 interposed between a stop screw 288 fixed in a lug 286 depending from the sleeve 278 and a spring-pressed stud 292 (Fig. 3) formed in a second lug 290 depending from the sleeve 278. This mechanism 110 forms an impositive connection between the rock shaft 280 and the sleeve 278 so that the punch plate can be yieldingly raised. At the other end of the rock shaft is fixed a depending arm 294 (Fig. 10) which is forked at its 115 lower end to receive a guide pin 296 on which slides a cam roller 298 for co-operation with any one of three cams 300, 302, 304. A spring-pressed stud 305 presses against the arm 294 to maintain the roller against its cam. These cams are formed with different 120 125 130

numbers of projections which vary directly with the frequency of the feeding movements of the backing strip. The cam roller 298 can be shifted opposite any one of these 5 cams by a fork 306 on the end of a shifting rod 308 slidably mounted in the frame and having a series of openings 310 (Fig. 6) into any one of which a spring-pressed plunger 312 may snap to secure the roller 10 opposite the desired cam. The three cams are fixed to a stud shaft 314 (Fig. 10) journaled in the base of the machine, a worm wheel 316 fixed to the shaft being driven by an intermittent worm 318 on the shaft 238.

15 It should be noted (Figs. 4 and 13) that the punch plate 264 normally rests on the anvil 250 and that the ledge 262 of the guide plate is normally below the lower surface of the punch plate. Consequently, when the 20 projections on the selected cam oscillate the arm 294 to raise the guide plate 256 and the clamp plate 266, the backing strip is first released for feeding movement and the subsequent contact of the ledge 262 with the 25 punch plate 264 raises the latter and the backing strip and keeps the punch embedded in the strip during the relief and feeding movements of the punch, thereby neutralizing the relief movement and causing the 30 punch to control the feed of the paper. The paper is not necessarily fed the full distance of the punch stroke, however, since the cams may be designed to keep the punch plate and backing strip raised only for a portion of 35 the punch stroke, thus lowering the paper from the punch before the latter reaches the end of its stroke.

As indicated in Fig. 4, the anvil is movable vertically to a slight extent in a vertical recess in the casting 324. A slot 320 40 in the anvil receives a wedge 322 having at the end a fork which is received in a groove 326 of a hand screw 328 threaded in the casting 324. This is merely a preliminary 45 adjustment to set the anvil and punch plate at the proper height to co-operate with the punch. The casting 324 and associated parts, including the punch plate and the work table, are mounted for horizontal ad- 50 justment on a shelf 330 (Fig. 3) on the frame, there being a groove 332 in the frame engaged by a collar 334 on an adjusting screw 336 threaded in a lug 338 of the casting 324. Clamping bolts 340 passing 55 through horizontally extending slots in the casting 324 serve to hold the casting and associated parts in the desired position, this adjustment moving the backing strip widthwise so that any portion of its width may be 60 fed to the punch. By this invention, therefore, a backing strip is utilized in all three dimensions. It is fed under the punch in the direction of its length, it can be adjusted widthwise so that the entire width is used,

and by punching several times in the same 65 area of the backing strip the thickness also is used. Formed as a part of the casting 324 are the substantially triangular ledges 342 to which the work table 20 is secured (Fig. 10) by screws. 70

Inasmuch as perforating machines often run at high speed and are frequently started and stopped, it is desirable to bring them to a stop as quickly as possible without shock. As the character of work varies, it is also 75 desirable to be able to vary the speed, as when operating on curved portions of a piece of work. This is accomplished by the mechanism shown in Figs. 14 to 17 in which 352 is a belt-driven pulley loosely mounted on the hub 354 of the friction pulley 356. The friction pulley is provided on one side face with a pair of spherical friction surfaces 358 for engagement with friction rolls 360 which, 80 on the opposite sides of their peripheries, bear against spherical friction surfaces 362 on a wheel or clutch member 364. Two clutch pins 366, projecting from the hub of the wheel 364, are housed within the cylindrical flange 367 which encloses a sleeve 370 carrying a clutch pin 368 normally pressed outwardly by a coil spring 372 to lie in the path of the clutch pins 366. position up to the maximum. To insure that the machine be stopped without shock, mechanism is provided to prevent the treadle rod from engaging the shoulder on the member 374 until after the machine has been slowed down. In other words, the stop can not be thrown in with the machine operating at high speed.

Pivottally carried by the end of the arm 398 is a hook 404 normally pressed by a spring 406 in a direction to snap over a lug 408 on the block 402. An extension 410 on the hook engages a stop pin 412 fixed to the machine frame when the mechanism is in the stopped position. A spring 414, which is weaker than the spring 388 above referred to, connects the end of the arm 398 with the treadle rod as shown in Fig. 14. Consequently, the spring 414 will give before the spring 388 will allow any change in the position of the friction rolls when starting the machine. The friction surfaces of the rolls and pulleys are pressed together with the desired pressure by a spring 416 interposed between nuts on the cam shaft 50 and a thrust bearing 418 at one end of the hub 354 and a similar thrust bearing 420 is interposed between the hub of the wheel 364 and the sleeve 370 to take the thrust in the other direction.

By the construction above described, depression of the treadle rod 378 first connects up the clutch so that the cam shaft is driven at low speed, the weak spring 414 stretching without affecting the stronger spring 388. As soon as the shoulder 401 on the block 402 engages the arm 398, said arm is swung downwardly to increase the speed of the machine, the stronger spring 388 then being positively stretched. During this movement the pivot of the hook 404 is carried downwardly so that the spring 406 causes the hook 404 to swing over and become locked to the lug 408. This relation of the parts continues while the machine is running at any speed above the lowest. When it is desired to stop the machine, the treadle rod is released, the spring 388 thereby swinging the friction rolls to the low speed position and swinging the arm 398 upwardly until the stop pin 412, by engagement with the extension 410, releases the hook 404 from the lug 408. Then and then only is the treadle rod allowed to rise further under control of the weak spring 414 in order to engage its end with the cam 376 and unlock the clutch and bring the machine to a positive stop by engaging the shoulder on the member 374. The spring 414 being weaker than the spring 388, the treadle rod is allowed to move down before the speed changing mechanism can overcome the tension of the spring 388.

Although the invention has been described by reference to a specific machine, it should

be understood that the invention, in its broader aspects, is not necessarily limited to the particular machine selected for illustration.

Having described my invention, what I claim as new and desire to secure by Letters Patent of the United States is:

1. In a perforating machine, in combination, a punch, a punch plate, a backing strip extending across said punch plate, means constantly tending to feed said strip across said punch plate, means for clamping said strip against said punch plate to receive the impact of a series of punchings, and means for releasing said clamping means to allow a feed movement of said strip. 80

2. In a perforating machine, in combination, a punch, a punch plate, a backing strip extending across said punch plate, means acting to pull said strip across said punch plate, means for clamping said strip against movement to receive in the same place the impact of a series of punchings, and means for releasing said clamping means to allow a feed movement of the strip after said series of punching movements. 90

3. In a perforating machine, in combination, a punch, a punch plate, a backing strip extending across said punch plate, means acting to feed said strip across said punch plate, means for clamping said strip against movement to receive the impact of a predetermined number of punchings, means for releasing said clamping means to allow a feed movement of the strip after said predetermined number of punchings, and means for varying said predetermined number of punchings. 100

4. In a perforating machine, in combination, a punch, a punch plate, a backing strip extending across said punch plate, means constantly tending to pull said strip across said punch plate, and mechanism for rendering said means effective at intervals to pull said strip over said block. 105

5. In a perforating machine, in combination, a punch, a punch plate, a backing strip extending across said punch plate, means for feeding said strip across said punch plate, a clamp plate disposed beneath the work and overlying the strip for clamping it to the punch plate, and an arm for actuating said clamp plate to release the strip for feeding. 110

6. In a perforating machine, in combination, a punch, means for operating said punch, a punch plate, a backing strip extending across said punch plate, means for feeding said strip across said punch plate, a clamp plate overlying the strip for clamping it to the punch plate, and a plurality of cams operated in timed relation to the punch operating means for selectively releasing the clamp plate with different frequency to 125

vary the time interval during which punching movements are carried out against a given portion of the backing strip.

7. In a perforating machine, in combination, a punch, a punch plate, a backing strip extending across said punch plate, means for feeding said strip across said punch plate, a clamp plate overlying the edges of said strip for holding it against feeding movement, an arm for actuating said clamp plate, a plurality of cams, a roller carried by said arm, and means for shifting said roller to co-operate with any one of said cams to vary the frequency of feed movement of the backing strip.

8. In a perforating machine, in combination, a punch, a backing strip, means for exerting tension on said backing strip, a clamp member to hold said strip against movement, and means for intermittently releasing said clamp member.

9. In a perforating machine, in combination, a punch, a backing strip, means for exerting tension on said backing strip, a clamp member to hold said strip against movement, means for releasing said clamp member at fixed intervals, and means for varying said intervals.

10. In a perforating machine, in combination, a punch, a backing strip, means for exerting tension on said backing strip, a clamp member to hold said strip against movement, and means for releasing said clamp member at fixed intervals, means for varying said intervals, said means comprising a shiftable roller and a plurality of cams.

11. In a perforating machine, in combination, a punch, a punch plate, a backing strip extending over said punch plate, means for actuating the punch to feed and punch the stock, means for clamping said strip against movement to receive, in the same place, the impact of a series of punching movements of the punch, and means for releasing said strip for feeding under control of the punch.

12. In a perforating machine, in combination, a punch, a punch plate, a backing strip extending over said punch plate, means for actuating the punch to feed and punch the work, means for holding said strip against movement to receive the impact of a series of punching movements of the punch, means for releasing said strip and moving said punch plate to cause the punch to remain embedded in the strip during one of its work feeding movements.

13. In a perforating machine, a punch, a punch plate, a backing strip, means for actuating the punch to feed and punch the stock, and means controlled by the machine for actuating the punch plate to cause the punch to control the feed of the backing strip.

14. In a perforating machine, in combina-

tion, a punch plate, a backing strip extending over said punch plate, a punch, means for actuating the punch to feed and punch the work, said actuation of the punch including a relief movement, and means for 70 yieldingly raising the punch plate to retain the punch embedded in the backing strip during the relief movement to feed the backing strip.

15. In a perforating machine, in combination, a backing strip, a punch, means for actuating the punch to feed the work step by step, means for causing said punch to feed the backing strip step by step with less frequency than the step by step feed of the work and means to vary the relative frequencies of feed steps of the strip and the work.

16. In a perforating machine, in combination, a punch, a punch plate, a backing strip extending across said punch plate, means for causing punching movement of the punch, means for retaining the punch plate and backing strip at a constant level 70 while a series of punching movements of the punch take place in the same area of the strip, and mechanism controlled by the machine for feeding said strip after said series of punching movements of the punch.

17. In a perforating machine, in combination, a punch, a punch plate, a backing strip extending across said punch plate, means for causing punching movement of the punch, means for retaining the punch plate and backing strip at a constant level 100 while a series of punching movements of the punch take place in the same area of the strip, means for actuating the punch to feed the work at every punching stroke, and mechanism for causing the punch to feed 105 the strip a step forward after each series of punching movements of the punch.

18. In a perforating machine, a work feeding punch movable horizontally to feed the work, an anvil, a punch plate normally supported by the anvil, a backing strip extending across said punch plate, means for raising said punch plate and backing strip intermittently so that the strip is impaled by the punch and fed thereby, and means 110 for varying the interval between raisings of the punch plate and strip.

19. In a perforating machine, a punch, an anvil, a punch plate normally supported by the anvil, a backing strip extending across said punch plate, a guide at the sides of the punch plate to guide the backing strip, and means for raising said punch plate and 115 backing strip.

20. In a perforating machine, a work feeding punch, an anvil, a punch plate normally supported by the anvil, a backing strip extending across said punch plate, a plate having a ledge underlying the punch plate, and means for actuating said plate 120

- to raise the punch plate and maintain the punch embedded in the backing strip during the feed movement of the punch.
21. In a perforating machine, a punch, a punch plate, a backing strip extending across said punch plate, a guide plate having a ledge underlying the punch plate, and means for actuating the guide plate to raise the punch plate and backing strip.
22. In a perforating machine, a punch, a punch plate, a presser foot, a backing strip extending across said punch plate, a clamp plate overlying the backing strip to hold it against the punch plate, and means for actuating the clamp plate to hold or release the backing strip.
23. In a perforating machine, a punch, a punch plate, a backing strip extending across said punch plate, a combined guide and clamp plate alongside the punch plate and having a flange overlying the backing strip to hold it against the punch plate, and means for releasably actuating the clamp plate to hold the backing strip.
24. In a perforating machine, a punch, a punch plate, a backing strip extending across said punch plate, a member having a flange overlying the backing strip to hold it against the punch plate and a ledge underlying the punch plate, and means for actuating the flanged member to release the strip and raise the punch plate.
25. In a perforating machine, a punch, an anvil, a backing strip extending across said anvil, a guideway on the anvil, a member slideable in said guideway and having a flange overlying the backing strip, and means for actuating said member to hold or release the strip.
26. In a perforating machine, a punch, an anvil, a backing strip extending across said anvil, a guideway on the anvil, a member slideable in said guideway and having a portion underlying the backing strip, and means for actuating said member to raise the backing strip.
27. In a perforating machine, a punch, an anvil, a punch plate normally supported by but separate from the anvil, and means for intermittently raising the punch plate away from the anvil.
28. In a perforating machine, a frame, spaced horizontal ways on said frame, rods having their end portions slideable in said ways, a vertical sleeve fixed to said rods for horizontal feeding movement, and a punch ram comprising a sleeve slideable in said vertical sleeve for punching movement.
29. In a perforating machine, a frame, a vertical sleeve slideable in said frame for horizontal feeding movement, a second sleeve slideable in said vertical sleeve for punching movement, a punch spindle rotatable in said second sleeve, and a member extending through both said sleeves for mov-
- ing the punch spindle to normal position at the beginning of the punching stroke.
30. In a perforating machine, a frame, a vertical sleeve slideable in said frame and having an opening, a second sleeve slideable in said vertical sleeve and having an elongated slot in alignment with the opening, a punch spindle rotatable in said second sleeve, and a cam member extending through said opening and said slot to move the punch spindle to normal position at the beginning of the punching stroke.
31. In a perforating machine, a work table, a hollow arm overhanging the work table, a sleeve slideable along the inside of the arm in the direction of the length of the arm, a work feeding punch having a T-shaped head and carried by the sleeve, means for sliding the sleeve to feed the work, and a lever co-operating with said T-shaped head to actuate the punch.
32. In a perforating machine, a work table, a hollow arm overhanging the work table and having bearings extending in the direction of the length of the arm, a plate closing the end of the arm and having bearings in alignment with said first bearings, a punch feeding member slideable in said bearings, and means for reciprocating the member to feed the work in alignment with the hollow arm.
33. In a perforating machine, a work feeding punch, means for actuating the punch to punch and feed the work, a presser foot to engage the work at one side of the path of the punch, a holddown for the work on the other side of the path of the punch, and a second holddown beyond the rearward limit of the path of travel of the punch.
34. In a perforating machine, a work feeding punch, means for actuating the punch to punch and feed the work, an edge gage at one side of the path of the punch, a holddown at the opposite side of the path of the punch, and a second holddown beyond the rearward limit of the path of travel of the punch.
35. In a perforating machine, a work feeding punch, means for actuating the punch to punch and feed the work, a holddown at one side of the path of the punch, a second holddown beyond the rearward limit of the path of travel of the punch, and means for adjusting said second holddown toward and from the punch in the line of feed.
36. In a perforating machine, a work feeding punch, means for actuating the punch to punch and feed the work, means for varying the feed stroke of the punch, a holddown near the rearward limit of the path of travel of the punch, and means for adjusting said holddown in the line of feed of the punch.
37. In a perforating machine, a work

feeding punch, means for actuating the punch to punch and feed the work, a hold-down at one side of the path of the punch, a second hold-down carried by the first, and 5 means for adjusting the second hold-down in the line of feed of the punch.

38. In a perforating machine, a work feeding punch, means for actuating the punch to punch and feed the work, a hold-down at one side of the path of the punch, 10 a second hold-down carried by the first, and means for adjusting both hold-downs toward and from the path of travel of the punch.

39. In a perforating machine, a work feeding punch, means for actuating the punch to punch and feed the work, a hold-down at one side of the path of the punch, a second hold-down carried by the first, means 15 for adjusting both hold-downs toward and from the path of travel of the punch, and means for adjusting the second hold-down in the line of feed of the punch.

40. In a perforating machine, in combination, a frame, a work feeding punch, a rod 25 extending horizontally from said frame at an angle to the path of work feeding movement of the punch, a block slideable along the rod, a work engaging member carried by the block, and a screw connection between 30 the rod and the block to furnish a fine adjustment for the work engaging member toward and from the line of feed of the punch.

41. In a perforating machine, in combination, a frame, a work feeding punch, a 35 guide rod on the frame at right angles to the path of work feeding movement of the punch, a member adjustable on the rod, a block slideable on the guide rod, a work engaging member carried by the block, and a 40 screw of small pitch threaded in the adjustable member and engaging the block for moving the block along the rod to furnish a fine adjustment for the work engaging member toward and from the line of feed of the 45 punch.

42. In a perforating machine, in combination, a frame, a work feeding punch, a guide on the frame, a member adjustably 50 mounted on the guide, a block slideable on the guide at right angles to the path of feeding movement of the punch, a work engaging member carried by the block, and a tangent screw connecting the adjustable member and 55 the block for moving the block and the work engaging member toward and from the line of feed of the punch.

43. In a perforating machine, in combination, a work feeding punch, a backing surface therefor, and an edge gage adjacent to the punch, said gage comprising a rigid arm 60 lying close to but out of contact with the backing surface, a gage member slidably mounted on the arm and a spring for hold-

ing the gage member yieldingly against the 65 backing surface.

44. In a perforating machine, in combination, a work feeding punch, a backing surface therefor, and an edge gage adjacent to the punch, said gage comprising a rigid 70 arm having its end overlying the backing surface, a gage member slideable on said end and bearing against the backing surface, and a spring interposed between the arm and gage member to hold the latter yieldingly 75 in contact with the backing surface.

45. In a perforating machine, in combination, a work feeding punch, a backing surface therefor, and an edge gage adjacent to the punch, said gage comprising a rigid 80 arm having at one end a cylindrical portion above the backing surface, a cylindrical casing slideably mounted on said portion, and a spring to hold the casing yieldingly 85 against said backing surface.

46. In a perforating machine, in combination, a work feeding punch, a backing surface therefor, and an edge gage adjacent to the punch, said gage comprising a rigid 90 arm overlying the backing surface, a gage member yieldingly mounted on said arm, and means for moving the arm to adjust the pressure of said gage member against the backing surface.

47. In a perforating machine, in combination, a work feeding punch, a backing surface, a block, a member having a stem 95 adjustably mounted in said block and an end portion overlying the backing surface, a gage member yieldingly mounted on said 100 end portion, and means for clamping said stem in said block to determine its adjusted position and thereby to adjust the pressure of said gage member against the backing surface.

48. In a perforating machine, in combination, a frame, a work feeding punch, a block, a work engaging member swivelled to the block to move in the line of feed of the punch, adjustable means contacting with 110 said work engaging member to move the latter in the line of feed, and a clamp for rigidly securing said member to said block in adjusted position.

49. In a perforating machine, in combination, a frame, a work feeding punch, a block having an inclined bearing, a work engaging member swivelled in said inclined bearing to move into and out of operative position, and adjusting screw contacting with 115 one side of said work engaging member to fix the limit of its movement toward the punch, and a clamp for securing said member to the block in operative or inoperative position.

50. In a perforating machine, in combination, a work feeding punch, a backing surface therefor, a block, a work engaging

member swivelled to the block to move in the line of feed of the punch and slideable in the block to move toward and from the backing surface, means contacting with said work engaging member to move the latter in the line of feed, and means for moving said member toward and from the backing surface.

51. In a perforating machine, a punch and a punch plate having relative movement of approach, a backing strip extending across said punch plate, and means for moving the punch plate and the backing strip transversely of the punch to utilize the width of the strip as a backing.

52. In a perforating machine, a reciprocating punch, a punch plate, a backing strip of flexible material extending across said punch plate, and means for moving the punch plate and backing strip transversely of the punch to utilize the width of the strip as a backing.

53. In a perforating machine, a reciprocating punch, a punch plate, a backing strip of flexible material extending across said punch plate, a guide for retaining the backing strip on the punch plate, and means for moving the punch plate and guide transversely of the punch to utilize the width of the strip as a backing.

54. In a perforating machine, a reciprocating punch, a punch plate, a supply reel, a backing strip of flexible material extending from said supply reel over said punch plate, and means for moving said supply reel and backing strip transversely of the punch to utilize the width of the strip as a backing.

55. In a perforating machine, a punch and a punch plate having relative movement of approach to perforate a piece of work, a flexible strip extending across said punch plate to act as a backing for the punch, and means for relatively moving the backing strip and punch to utilize both the width and the thickness of the strip as a backing.

56. In a perforating machine, a reciprocating punch, a punch plate, a flexible strip extending over said punch plate to act as a backing for the punch, means for feeding the strip lengthwise over the punch plate to utilize the length of the strip, means for moving the strip laterally to utilize the width of the strip, and means for relatively moving the punch and punch plate to utilize the thickness of the strip.

57. In a perforating machine, in combination, a punch plate, a backing strip extend-

ing over said punch plate, a punch, and means for causing the punch to feed either 60 to the work or the backing strip.

58. In a perforating machine, in combination, a punch plate, a backing strip extending across said punch plate, means for intermittently feeding said strip to bring successive portions of the strip into operative relation to said punch plate, and means for moving the backing strip transversely of the direction of feed of said strip to utilize both the width and the length of said strip as a 70 backing.

59. In a perforating machine, a punch and a punch plate having relative movement of approach to perforate a piece of work, a flexible backing strip extending across said 75 punch plate, means for intermittently causing said punch to feed the backing strip in a direction angularly related to the direction of the relative movement of approach, and means for moving said strip laterally with 80 respect to the direction of feeding movement thereof.

60. In a perforating machine, a reciprocating punch, a punch plate, a flexible strip extending over said punch plate to act as a 85 backing for the punch, means for causing said punch to feed the strip lengthwise over the punch plate to utilize the length of the strip, means for moving the strip laterally with respect to the punch plate to utilize the 90 width of the strip, and means for relatively moving the punch and punch plate to utilize the thickness of the strip.

61. In a perforating machine, in combination, a punch, a punch plate, a backing strip, 95 extending over said punch plate, means for actuating the punch to feed and punch the stock, means for clamping said strip against movement to receive, in the same place, the impact of a series of punching movements of 100 the punch, means for exerting tension on said backing strip tending to pull it forward, and means for releasing said strip for feeding under control of the punch.

62. In a perforating machine, a reciprocating punch, a punch plate, a flexible strip extending over said punch plate to act as a 105 backing for the punch, means for feeding the strip lengthwise over the punch plate to utilize the length of the strip, and means for 110 moving the strip laterally to utilize the width of the strip.

In testimony whereof I have signed my name to this specification.

PERLEY R. GLASS.

DISCLAIMER

1,580,132. -*Perley R. Glass*, Wayland, Mass. PERFORATING MACHINE. Patent dated April 13, 1926. Disclaimer filed February 4, 1931, by the assignee, *United Shoe Machinery Corporation*.

Hereby enters this disclaimer to said claims 58 and 62 of said Letters Patent, which are in the following words, to wit:

"58. In a perforating machine, in combination, a punch plate, a backing strip extending across said punch plate, means for intermittently feeding said strip to bring successive portions of the strip into operative relation to said punch plate, and means for moving the backing strip transversely of the direction of feed of said strip to utilize both the width and the length of said strip as a backing."

"62. In a perforating machine, a reciprocating punch, a punch plate, a flexible strip extending over said punch plate to act as a backing for the punch, means for feeding the strip lengthwise over the punch plate to utilize the length of the strip, and means for moving the strip laterally to utilize the width of the strip."

[*Official Gazette February 24, 1931.*]
